UNITED STATES PATENT OFFICE.

CECIL H. BOYULS, OF LOUISVILLE, KENTUCKY, ASSIGNOR OF ONE-FOURTH TO ADOLPH A. MYERS AND ONE-FOURTH TO MILTON A. MYERS, BOTH OF LOUISVILLE, KENTUCKY.

GARMENT-FORMER.

1,310,602.

Specification of Letters Patent.

Patented July 22, 1919.

Application filed August 6, 1918. Serial No. 248,513.

To all whom it may concern:

Be it known that I, CECIL H. BOYULS, a citizen of the United States, residing in Louisville, county of Jefferson, and State of Kentucky, have invented a new and useful Garment-Former, of which the following is a specification.

This specification relates to a method of ironing shirt sleeves.

10 The method by which shirt sleeves are most generally ironed, is to spread the sleeves out smoothly on a padded flat surface and move a "heated flat iron" manually to and fro over it, until the wrinkles are all removed. This 15 method is too slow for the modern commercial laundry so recourse has been had to other methods such as pressing the sleeve between two padded steam heated surfaces; another method is placing the sleeve between 20 a padded rotatable roll and a concave heated iron, which conforms to, and extends about, a portion of the circumference of the roll, and exerting traction on the sleeve as the roll turns. These methods while more 25 speedy than that of the old style flat iron are not as efficient as desired inasmuch as unnecessary time and labor is consumed in spreading out and preparing the sleeve for subjection to the action of the machine.

30 An object of this invention is to provide a method of ironing shirt sleeves which will not require a preliminary preparation of the sleeve before subjection to the action of the device by means of which the ironing is accomplished.

A further object is to provide means of the character described which may be economically constructed and which will be efficient in service and durable in operation.

40 The invention may be understood from a consideration of the following detailed description taken in connection with the accompanying drawing which forms a part of the specification, with the understanding however that while the drawing shows a practical embodiment of the invention, the latter is by no means limited to exact conformity therewith, but may be embodied in any other form which may come within the scope of 45 the claims appended hereunto.

In the drawing wherein similar reference characters designate like parts in the several views, Figure 1, is a side elevation of 50 an embodiment of the invention: Fig. 2, a

central vertical longitudinal section: Fig. 3, 55 a transverse section on line 3-3 of Fig. 1.

Referring now to the drawing the reference character —11— indicates a stand, or table, which may be of any usual or desired construction, on which is secured a pedestal 60 —12—, which comprises a flange —13— and a column —14—. This column may be arranged at a suitable angle, preferably 45 degrees, and as illustrated it is hollow and is counterbored at —15— to receive a stem 65 —16— which in turn supports a form —17—. The form which is highly polished on its outer surface is hollow, elliptical in cross section, and its longitudinal contour similar to that of a shirt sleeve, the upper edge 70 —18— being a straight line, and the lower edge —19— curved, as from the arm-hole to the cuff of a sleeve. A reduced portion —20— of the form corresponds to the cuff of a sleeve. The form terminates in a 75 rounded end portion —21—. Near its rear end, the form is provided with a transverse partition —22— which has an aperture to receive the end of the stem 16, a flange —23— fitting against the partition, the surfaces being 80 so finished that a steam tight joint is secured. The heads of cap-screws —24— bind on the edge of the flange 23, and serve to retain the parts in their relative positions. By loosening the cap screws the form may 85 be adjusted about its axis to give it the position which best suits the convenience of the operator. The stem is provided with a longitudinal passage —25— in the inner end of which is secured a pipe —26—, which extends forward and terminates in proximity to the head of the form. A pipe —27— secured in the outer end of the passage 25, leads to a suitable source from which steam 90 is supplied to heat the form. A second passage —28— conducts the water of condensation to a drain pipe —29—.

In operation live steam is admitted to the interior of the form through the pipe 26, whereby it is delivered close to the forward 100 end, heating it to a suitable temperature. The water of condensation accumulates in the lower end until it overflows through the passage 28. An operator then takes position along side, with a number of shirts, properly 105 conditioned for ironing, within convenient reach, grasping a shirt, with both hands, in proximity to an arm hole, she inserts the

form into the sleeve through the arm hole, in such a manner that the upper edge of the sleeve will correspond with that of the form, and draws the sleeve down over the form 5 until an offset —30— engages with the cuff band. The cuff band is then grasped and the sleeve pulled from off the form. The material being slightly elastic it is readily drawn tightly about the form, every wrinkle 10 and crease being obliterated the heat of the form setting the fabric in that form, the edges of the form producing creases which aid in the folding of the sleeve. After removing the sleeve from the form, the gathers 15 along the cuff may be ironed by grasping the cuff at each end stretching it tightly and rubbing the gathers longitudinally on the rounded head 21. As the operator has but to pull the sleeve on the form and off again, 20 no preliminary preparations being necessary, nor operation required while the sleeve is on the form, the work may proceed very rapidly.

Having thus described my invention so that others skilled in the art pertaining thereto can make and use the same, I claim: 25

1. A device as characterized comprising a pedestal, a stem positioned therein, a closed hollow form contoured to resemble a sleeve having a straight upper edge and a curved 30 lower edge, there being an offset in the edges a spaced distance from the forward end, said form being adjustably fitted on said stem and the stem having inlet and exhaust passages therethrough. 35

2. A device as characterized, comprising a hollow form contoured to resemble a sleeve, elliptical in cross section, and having a straight upper edge and curved lower edge, there being an offset in the edges thereof of a spaced distance from the forward end adapted to limit the movement of a sleeve thereonto, the forward end being rounded and polished. 40
